UNITED STATES PATENT OFFICE.

ROSS M. G. PHILLIPS, OF MINNEAPOLIS, MINNESOTA, ASSIGNOR TO THE AUTOMATIC STOVE CO., OF MINNEAPOLIS, MINNESOTA, A CORPORATION.

COOKER.

1,179,961.

Specification of Letters Patent. Patented Apr. 18, 1916.

Application filed December 21, 1912, Serial No. 737,993. Renewed August 14, 1915. Serial No. 45,572.

To all whom it may concern:

Be it known that I, Ross M. G. PHILLIPS, a citizen of the United States, residing at Minneapolis, in the county of Hennepin and State of Minnesota, have invented a new and useful Improvement in Cookers, of which the following is a specification.

The object of this invention is to provide a portable cooker having improved means for controlling the fire and draft automatically.

The invention further has beneficial effects by providing improved features of construction and combination of parts which will be hereinafter fully described and claimed.

The invention combines efficiency and effectively a stove and fireless cooker, adapted to burn gas or hydrocarbons such as alcohol, kerosene or gasoline.

In the accompanying drawings forming part of this specification, Figure 1 is a plan view of an automatic cooker embodying my invention; Fig. 2 is a view thereof in front elevation; Fig. 3 is an enlarged section on the line W—W of Fig. 2; the parts being shown when in closed position; Fig. 4 is a section on the line W—W, Fig. 2 when the parts are in open position; Fig. 5 is a section on the line Y—Y, Fig. 3; Fig. 6 is a sectional detail of the lower portion of the cooker showing the construction of part of the burner; Fig. 7 is a side view of a detail illustrating the construction by which the main shut off valve for the burner is adapted to be operated; Fig. 8 is a plan of the supporting sleeve and lever for the insulated receptacle; Fig. 9 is a side view of a detail showing the construction of part of the time mechanism for closing the receptacle automatically; Fig. 10 is a plan of the construction illustrated in Fig. 9; Fig. 11 is a detail illustrating the slot plate which is marked to indicate when the receptacle C is in its raised or heat-charging position, and when in its lower or heat-consuming position; Fig. 12 is a vertical section through the rack for holding cooking utensils and which is adapted to be placed in the insulated receptacle; Fig. 13 is a perspective of one of the removable shelves on the rack; Fig. 14 is a detail of one of the sides of the rack and Fig. 15 is a section upon the line Z—Z, Fig. 14. Fig. 16 is a broken detail view showing the parts em-

ployed for manually opening the gas valve and automatically closing it, the valve being shown in its open position by full lines, and in its closed position by broken lines.

In the drawings A indicates a suitable outer casing having an open top and formed with a door way 2 near the lower portion of one of its sides. A tray 3 is adapted to slide freely on the bottom 4 of the casing through the door way, its end 5 projecting below the door 6, in the door way so that it can be used as a handle to draw the tray out or push it into the casing. This tray is adapted to carry a pre-heater B such as a gas burner having a shallow bowl 7 mounted upon a step 8 struck upwardly in the tray 3 and secured thereto by means of a screw 9. The burner cap 10 is placed on said bowl and is provided with gas openings 11 in nipples 12 projecting above the level of the surface of said cap. A strainer 13 is interposed between the cap 10 and bowl 7. At the door end of the bowl a gas needle valve 14 is secured by threading it into a wall of the bowl, said valve being controlled through the door way 2 by the handle 15. This valve is adapted to admit gas into the mixing chamber 16 which is formed in the casing and connected with the inner chamber 17 below the perforations in the burner cap by means of the passage 18. The bowl 7, called, of the preheater or burner B is formed with a wide flange 7^a concentric with the burner B except at its forward end where it is increased in width 90 and extended symmetrically forward so that the whole flange when looked down upon (Fig. 5) is pear-shaped in general outline. This flange receives a sealing and insulating pad 7^b of asbestos or other equivalent material, the said pad being formed with a large circular opening for the reception of the burner B and with a rectangular opening providing for the location of a mixing-chamber 16 between the burner B 100 and the needle-valve 14. When the food container C descends by gravity it is brought to a bearing upon the sealing and insulating pad 7^b by means of which it is insulated and the radiation of its heat prolonged. When the food container C descends upon the pad 7^b, the bottom of the container entirely covers the burner B and the mixing-chamber 16, and thus effects the closure of the ingress draft-passage 38 in 110

the lower end of the container and also the closure of the said mixing-chamber. In this passage 18 a tube 19 is adapted to slide longitudinally to and from the inner end of the valve 14 thus regulating the proportion of air admitted with the gas into the inner chamber 17 below the burner plate. The regulating tube 19 is adapted to be adjusted by means of a pull rod 20 having a handle 21 positioned on the outer end of the casing and conveniently situated so that it can be operated through the door way.

The valve 14 is connected by the pipes 22 and 23 and flexible tube 24 with a source of gas supply not shown (see Fig. 5). The flexible tube 24 permits the burner being moved with the tray through the door way for cleaning purposes thus rendering the burner portion of the appliance thoroughly sanitary and efficient and effective in operation. The tray 3 is adapted to slide in a pair of longitudinal grooves 25 in the base portion of the outer casing. The pipe 23 is secured to the wall of the outer casing and is provided with a main shut off valve 26 to which the flexible tube 24 is connected. The valve stem 27 of the valve 26 carries a lever arm 28 by which the valve is adapted to be closed automatically in a manner to be hereinafter described. It also carries an operating arm 29 to which a pull rod 30 is connected having a handle 31 by which the rod can be operated in and out through the casing to open and close the main shut off valve by hand.

The door 6 is secured to the front wall of the outer casing along its lower edge by means of the hinge connection 32 and carries upon its inner face a mirror 33. This door is adapted to swing outwardly and downwardly to assume an effective angle whereby the burner can be seen by an attendant when looking downwardly upon the mirror, the swinging movement of the door being limited by a stop shoulder 34 in the form of a strip which is secured to the outer face of the door. A catch 35 is provided by which the door may be locked in closed position, said catch being adapted to engage over the upper edge of the door way.

The rim of the outer casing extends inwardly and is turned down to form a centrally disposed depending cylindrical wall 36 in which an insulated food-container or receptacle C is adapted to slide vertically and freely. This receptacle has a double side and bottom wall, the space between the adjacent inner faces of said walls being filled with suitable poor heat conducting material 37 such as ground cork. The bottom of the receptacle is formed with a centrally disposed opening 38 fitting over the burner of the pre-heater B and its top is closed by a removable cover 39 having double walls spaced apart for insulating purposes.

The space between the walls of the cover may also be filled with poor heat conducting material such as cork when desired, although it is obvious the receptacle and cover may be used without any filling between the spaced walls, tight air spaces being employed instead.

The cover is provided with a centrally disposed egress draft passage 40 which is adapted to be closed by an automatically operated valve 41, said valve being provided with a tubular stem 42 having a passaged head 43 upon its upper end. The passage through the tube and head is adapted to communicate by the valve 41 with the chamber formed by receptacle C and the cover therefor, through a port 44, said port being adapted to be closed by a safety valve in the form of a loose ball 45 in the space left between the lower end of the tube and a bushing 46 which is secured in the valve 41 and provided with said port 44. This ball valve 45 is adapted to give vent to excessive pressure of steam in the cooker and is adapted to operate automatically independent of the valve 41 when the receptacle is closed. The valve 41 is adapted to be held in open position by a lever arm 47 which is fulcrumed upon the top of the cover 39 by means of the journal connection 48. The inner end 95 of this lever arm 47 passes freely over the tubular stem 42 and has coiled spring 49 over said stem interposed between its end and the upper surface of the valve 41. When the lever arm 47 is tilted down it closes the valve 41 under spring pressure over the passage 40 in the cover. The outer end 50 of the lever arm 47 is adapted to strike against a tubular standard 51 which is mounted upon the outer casing A. The end 50 may be inserted in said standard to support the cover when removed. When the insulated receptacle is in superior position as illustrated in Fig. 4 the lever arm 47 tilts up through the action of the expansion spring 52 interposed between the inner end of the lever arm and the top of the cover, thus lifting the valve 41 off of its seat and opening the passage through the cover. When the insulated receptacle and valve 41 are in open or superior position a draft passage is produced through the insulated receptacle whereby air in desired quantity is admitted to the burner through the door way 2 and is heated by the burner and passed upwardly through the insulated receptacle.

The receptacle C is adapted to be seated in the sleeve D (see Fig. 8) which in turn is supported freely within the wall 36 by a fulcrum arm 53 in the form of a yoke the sides of which are secured to the sleeve by pivots 54. The ends 55 of the yoke are hung by lugs 56 and brackets 57 from the outer casing, said brackets being secured between the cylindrical wall 36 and the outer wall of

the outer casing. The median portion of the fulcrum arm or yoke 53 passes freely outside of the sleeve D and within the outer wall of the outer casing and is free to swing 5 up and down whereby the sleeve D engaging below the shoulder 58 of the insulated receptacle is adapted to raise and lower the same. When lowered the insulated receptacle closes the mixing chamber 16 preventing 10 air entering said receptacle through the gas burner.

A supporting rod 59 depends freely through an opening 60 in the rim of the outer casing and is secured freely to the 15 median portion of the yoke by means of the bracket 61. This supporting rod is provided with a handle 62 and formed with a shoulder 63 which is adapted to catch over the edge 64 of the slotted plate 65 surrounding the opening 60 to hold the median portion of the yoke up and the insulated receptacle in superior position as illustrated in Fig. 4 so that a draft opening is formed 20 between the pre-heater and the inner receptacle. The operating lever 28 on the gas valve 26 is positioned in the path of an arm 90 (see Fig. 8) on the yoke 53 whereby I permit the gas valve 26 to be manually opened by the rod 30 when the cooking receptacle C is in its raised or heat-charging position, as well as provide for automatically cutting off the supply of gas from the burner when the said receptacle C descends into its lower or heat-conserving position, 35 and whereby also the said gas-valve 26 is prevented from being opened except when the receptacle C is in its raised or heat-charging position. By reference to Fig. 16 it will be seen that when the receptacle C has 40 been lifted into its raised position, the manual operation of the rod 30 will cause the arm 88 to be lifted into position to be operated upon by the arm 90 the moment the said receptacle begins to descend following 45 the automatic disengagement of the shoulder 63 from the left hand edge of the supporting-plate 65. The slot 64 (see Fig. 11) and the free connection between the lifting rod 59 and the bracket 61 allows the rod 59 when raised or lowered to be moved laterally and either extreme position of said rod 50 in said slot is indicated by the words "On" and "Off" which are suitably inscribed upon the surface of the supporting-plate 65. The 55 lateral movement of the lifting-rod 59 to automatically disengage its supporting-shoulder 63 from the left hand edge or "on" side of the opening 60 in the said plate, is effected by suitable timing mechanism to be 60 hereinafter described.

A stand 66 of skeleton form is adapted to be placed in the lower end of the insulated receptacle around the draft passage 35 upon which a heat conserver 67 in the form of a disk made of stone, metal or other suitable

material is adapted to be placed, said stand serving to place the heat conserver above the draft passage without obstructing it to the entrance of heated air. A rack E may be employed in the receptacle for holding 70 the cooking utensils or articles to be cooked may be placed directly upon the heat conserver or on the bottom of the insulated receptacle when desired.

The rack illustrated consists of a base 75 ring 68, flanged downwardly to reinforce its strength and secured rigidly to a pair of vertical oppositely disposed side plates 69 which are provided with hinged bale handles 69 by which the rack can be lifted 80 out or placed in the insulated receptacle upon the heat conserver or the stand, the handles being turned inwardly below the cover to economize space. A plurality of 85 horizontal shelves illustrated in the form 85 of flat rings 70 are adapted to be detachably secured in vertically selected positions upon said side plates, the positioning of these shelves permitting the placing of cooking utensils of different shapes and heights 90 upon the rack as desired. The ring of each shelf is mounted upon a transverse support 71, the ends of which are turned down to produce tongues 72 which may be removably inserted below straps 73, said straps 95 being secured in suitable position across each side bar as illustrated in Figs. 12 to 15 inclusive.

The timer F is adapted to release the supporting rod 59 to permit the insulated receptacle to drop and simultaneously shut off the supply of gas to the burner and cause the valve 41 to close the opening in the cover, thereby sealing the insulated receptacle. This timer employs a clock work mechanism 75 of ordinary construction which is adapted to push the rod 59 out of engagement with the edge 64 at a pre-determined time through the action of the push rod 76 which is slidably and pivotally mounted on the pin 77 on the wall of the outer casing. The push rod 76 co-operates with the link 78 forming a pair of toggle levers the connected ends of which being pivoted at 79, to the actuating link 80. This actuating link is 100 pivotally mounted on the arm 81, one end of which is fulcrumed at 82 on the casing A and its free end provided with a handle 83 projecting through and movable in the slot 84 (see Fig. 2) in the casing. Near the free end of the arm 81 is a stop 85 adapted to drop into the notch 86 in the periphery of the stop wheel 87 carried by the main drive shaft 88 of the clock work mechanism. The crank handle 89 on the shaft 88 is adapted to be moved in the direction indicated by the arrows in Figs. 2 and 9, a portion of a turn according to the length of time the pre-heater is to be operated. The degree of turn 105 illustrated being marked 15 and 30 (indi- 110

115 120 125 130

cating minutes, starting at zero) upon the casing A (see Fig. 2). When the crank handle 89 is in zero position and the insulated receptacle closes the rod 59 is free to be lifted and its shoulder engaged over the edge of the plates 65. The rod 59 however cannot be set in position until the crank handle 87 has been moved from zero position and set for the desired number of minutes the device is to be operated. The raising of the rod 59 lifts the insulated receptacle and permits the opening of the main control valve 26 through the operation of the pull handle 31. The turning of the crank handle 89 winds the clock work mechanism and after the clock work mechanism operates for a pre-arranged time the stop wheel 87 revolves until the stop 85 engages the notch 86 whereupon the spring 88 secured under tension to the outer casing and the arm 81, lifts said arm with its stop 85 into engagement with the notch 86 thus stopping the clock work mechanism and tilting the arm 76 causing its outer end to push the rod 59 in the direction of the arrow indicated in Fig. 9 out of engagement with the edge 64 thus releasing the insulated receptacle and causing it to close over the burner, and shut off the supply of gas.

In operation after the rack and the cooking utensils have been placed in the insulated receptacle the cover 39 is adjusted over said receptacle with the lever arm 50 placed over the standard 51. The timer is then set for the desired number of minutes the burner is to be operated and the handle 62 raised and engaged in position over the edge 64 of the plate 65. In this position the valve 41 is opened as illustrated in Fig. 4 through the operation of the spring 52 and lever arm 47. The door 6 is then opened and pull rod 30 drawn out opening the main control valve 26. The gas from the burner is then ignited and the remainder of the operation is automatic as fully set forth in the above description. The amount of gas and air admitted to the burner may be regulated from time to time by adjusting the gas valve 14 and the regulating tube 19 by means of the handles 15 and 21 so as to produce proper combustion of fuel which can be ascertained by looking down into the mirror 33 and inspecting the condition of the flame.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

I do not broadly claim in this application a food-container and preheater one of

the said parts being movable with respect to the other, combined with spacing-mechanism the releasing function of which is controlled by automatic mechanism, and other broad features which are claimed in my co-pending application Serial No. 710,630 filed July 20, 1912.

The term "cocking means" is used herein to express the embodiment and mode of operation which is very essential to successful cooking, and which I believe to be an entirely new idea of means in this art. In other words, in the construction above described, the valve shutting off the fuel supply is manually opened, subject to a force (which is illustrated as the weight of the chamber but is not limited thereto) constantly tending to close the valve but held in abeyance by a device (which is here illustrated as the shoulder 64, but is not limited thereto) capable of being tripped or released by the timer so as to permit the cocked parts to return quickly and automatically to uncocked position. This same mode of operation in the above described construction also controls the unsealing and sealing of the cooking chamber. The successful cooking apparatus should be adapted for maintaining preheating conditions subject to a widely varying range of time, to be determined by the cook in accordance with the article to be cooked. These variations may extend all the way from a few minutes to a very much longer time. At the expiration of this time, whatever it may be, the cooking apparatus should automatically terminate the preheating or fire cooking conditions and convert them, without human attention, into final or fireless cooking conditions. Now the cocking means above referred to is of great importance because the operator may set and cock the device to a point corresponding with any time or preheating or fire cooking that the article to be cooked demands, and thus place the device in a position to be tripped or discharged automatically by the timer at the precise time when the preheating conditions are to be converted into final or fireless cooking conditions.

An idea of means embodied in the apparatus above described which I believe to be an entire innovation in this art is automatic mechanical means for effecting without human attention the transition from cooking with fire to cooking without fire, whereby the cooking which is begun in an open oven heated by a fire, is continued and completed in the same oven by conserved heat, all without any attention on the part of the cook other than to set the apparatus and light the fire.

The force or energy employed to terminate the period of fire cooking is stored, in the construction shown and described, by

the means employed for lifting the food-container at the time of setting of the apparatus, this energy or force being restrained or held in abeyance during the period of fire-cooking by the cooking means and released by the automatic operating means which is adapted to be manually set for varying the period of fire-cooking as occasion may demand, whereby the relation of the period of fire-cooking to the period of fireless-cooking may be pre-arranged by the operator prior to the use of the apparatus which automatically makes the transition from fire- to fireless-cooking

15 in consonance with the preparatory manual setting of the apparatus by the operator.

Having described my invention, what I claim as new and desire to protect by Letters Patent is:—

20 1. In a cooking apparatus, the combination with a food-container, of a preheater, one of the said parts being movable with respect to the other, spacing-mechanism for holding the said movable part in spaced relation to the other part, means for automatically controlling the releasing function of the spacing-mechanism, means for supplying fuel to the preheater, and means for automatically controlling the said means 25 of fuel-supply.

2. In a cooking apparatus, the combination with a food-container and a preheater, one of the said parts being movable with respect to the other, spacing-mechanism for holding the said movable part in spaced relation to the other part, means for automatically controlling the releasing function of the said spacing-mechanism, means for supplying fuel to the preheater, and means 35 for utilizing the movement of the said movable part for automatically shutting off the supply of fuel to the preheater.

3. In a cooking apparatus, the combination with a vertically movable food-container having ingress and egress draft-passages, of a preheater adapted to act as a closure for the said ingress draft-passage, spacing-mechanism for holding the said container in spaced relation to the preheater, means for automatically controlling the releasing function of the spacing-mechanism, means for supplying fuel to the preheater, and means operated by the descent of the food-container for automatically operating the said fuel-supply means.

4. In a cooking apparatus, the combination with a vertically movable food-container having ingress and egress draft-passages, of a preheater adapted to act as a closure for the said ingress draft-passage and provided with a mixing-chamber, spacing-mechanism for holding the said container in spaced relation to the preheater, means for automatically controlling the releasing function of the spacing-mech-

anism, means for supplying fuel to the mixing-chamber of the preheater, and means controlled by the movement of the container for automatically controlling the supply of fuel to the said mixing-chamber. 70

5. In a cooking apparatus, the combination with a vertically movable food-container having ingress and egress draft-passages, of a preheater adapted to act as a closure for the said ingress draft-passage 75 and provided with a mixing-chamber, a sealing pad mounted upon the preheater and having openings for the burner of the said preheater and for the said mixing-chamber, spacing-mechanism for holding the said container in spaced relation to the preheater, and means for automatically controlling the releasing function of the spacing-mechanism.

6. In a cooking apparatus, the combination with a vertically movable food-container having ingress and egress draft-passages, of a preheater adapted to act as a closure for the said ingress draft-passage, one of the said parts being movable relative 90 to the other; spacing-mechanism for holding the said movable part in spaced relation to the other part, means for automatically controlling the releasing function of the spacing-mechanism, a fuel valve for supplying fuel to the preheater, and means controlled by the movement of the said movable part for automatically operating the said fuel-valve.

7. In a cooking apparatus, the combination with a vertically movable food-container having ingress and egress draft-passages, of a laterally movable tray, a preheater mounted thereupon and adapted to act as a closure for the said ingress draft-passage, spacing-mechanism for holding the container in spaced relation to the preheater, means for automatically controlling the releasing function of the spacing mechanism, a fuel-valve for the preheater, and means for automatically closing the said fuel-valve when the food-container descends.

8. In a cooking apparatus, the combination with a vertically movable food-container having ingress and egress draft-passages, of a preheater acting as a closure for the said ingress draft-passage, spacing-mechanism for holding the said food-container and preheater in spaced relation, 120 means for automatically controlling the releasing function of the spacing-mechanism, a fuel-valve for the preheater, and means for manually opening the said fuel valve when the container is in its elevated position and for utilizing the descent of the said container for automatically closing the said valve which cannot be opened except when the container is in its raised position.

9. In a cooking apparatus, the combina- 130

- tion with a vertically movable food-container having ingress and egress draft passages, of a preheater acting as a closure for the said ingress passage, spacing mechanism 5 for holding the container in spaced relation to the preheater, means for automatically controlling the releasing function of the spacing mechanism, a fuel valve for the preheater, manually operable means for 10 opening the said valve when the container is raised, means automatically operated by the descent of the container for closing the said valve, which is held closed by the weight of the container when the same is 15 released.
10. In a cooking apparatus, the combination with a fuel-supply valve, means tending to automatically close the same, means for manually cocking the said automatic 20 closing means in operating position, automatic operating mechanism, means for manually setting the said automatic operating mechanism, and connections with said automatic operating mechanism, whereby said 25 cocking means is tripped as desired.
11. In a cooking apparatus, the combination with a cooking compartment, having an egress draft passage, of a closure for the same, cocking means for maintaining the 30 said closure in its open position, automatic operating mechanism for releasing the cocking means as desired to permit the closure to close the said passage, means for manually cocking the closure in its open position subject 35 to the action of the said automatic operating mechanism, a burner, and a fuel-supply automatically controlled and closed by the said automatic operating mechanism, and manually opened after the setting of the 40 cooking means.
12. In an automatic cooking apparatus, the combination with a cooking compartment having an ingress draft passage and an egress draft passage, of closures for the 45 said passages, cocking means for maintaining the said closures in their open positions, automatic operating mechanism for releasing the closing means as desired to permit the closure of the closures, manually operable means for setting the cocking means subject 50 to the action of said automatic operating mechanism, a burner, and a fuel-supply for supplying fuel thereto and adapted to be automatically controlled in closing 55 by the said automatic operating mechanism, and to be manually opened after the setting of the cocking means.
13. In a cooking apparatus, the combination with an insulated oven containing ingress and 60 egress draft passages, a closure for sealing said ingress draft passage, a closure adapted to said ingress draft passage, a closure for sealing said egress draft passage, a closure for sealing the oven without the said egress draft passage, operating mechanism, a handle, and means for 65 said automatic operating mechanism, including 70 usually set, connections whereby the said automatic operating mechanism controls the automatic sealing of the oven by said egress draft-passage closure, a valve controlling the supply of fuel to said burner, connections with said automatic mechanism, whereby said valve is automatically closed when the oven is sealed, and a handle whereby said valve is manually opened.
14. In an apparatus for conjoint fire- and fireless-cooking, the combination with a 75 cooking compartment having means for sealing and unsealing it, of a fuel-supply, cocking means for maintaining the apparatus in adjustment for fire-cooking and the storage of heat for fireless-cooking, automatic operating mechanism adapted to release the said cocking means, whereby the cooking compartment is automatically and concurrently sealed and the fuel-supply shut off, and means independent of the said fuel-supply for manually cocking the cocking means and setting the said automatic operating mechanism.
15. In a cooking apparatus for conjoint fire- and fireless-cooking, the combination with a cooking compartment having a burner-opening, of a burner co-acting with the said opening, a fuel-supply for the said burner, cocking means for maintaining the 80 apparatus in adjustment for the use of the burner, automatic mechanism adapted to release the said cocking means for turning off of the fuel-supply, means independent of the said fuel-supply for manually cocking the 85 cocking means preparatory to fire-cooking and to the storage of heat for fireless-cooking, and means for manually turning on the fuel-supply.
16. In a cooking apparatus for conjoint fire- and fireless-cooking, the combination with a cooking compartment, of a burner, a fuel-supply therefor, cocking means for maintaining the apparatus in adjustment for the use of the burner for fire-cooking and 90 the storage of heat for fireless-cooking, automatic operating mechanism for turning off the fuel-supply and so extinguishing the burner to terminate the period of fire-cooking and to begin the period of fireless cooking, means independent of the said fuel-supply for manually cocking the cocking means for setting the apparatus preparatory to fire-cooking, and means independent of the 95 said cocking means and the said automatic operating mechanism for the control and regulation of the said fuel-supply.
17. In a cooking apparatus for conjoint fire- and fireless-cooking, the combination with a cooking compartment having a 100 burner-opening and an egress draft-passage, of a burner, a fuel-supply therefor, cocking means for maintaining the apparatus in adjustment for the use of the burner, automatic operating mechanism for releasing the 105

5 said cocking means, whereby the fuel-supply is turned off, means independent of the said fuel-supply for manually cocking the cocking means and for setting the apparatus, 5 and independent manually operable means for turning on and shutting off the fuel-supply.

10 18. In a cooking apparatus for conjoint fire- and fireless-cooking, the combination with a cooking compartment having a burner-opening and an egress draft-passage, of a burner co-acting with the said opening, a closure for the said passage, a fuel-supply for the said burner, cocking means for maintaining the apparatus in adjustment for the use of the burner, automatic mechanism adapted to release the said cocking means for shutting off the fuel-supply and permit the closing of the closure, means independent of the said fuel-supply for manually cocking the cocking means and setting the said automatic operating mechanism, and means independent of the said cocking means and the said automatic operating 25 mechanism for the control and regulation of the said fuel-supply.

15 19. In a cooking apparatus for conjoint fire- and fireless-cooking, the combination with a cooking compartment, of a burner arranged in heating relation thereto, a fuel-supply, means for storing energy for terminating the period of fire-cooking, cocking means for restraining the energy so stored, automatic operating means for releasing the 30 cocking means and so permitting the stored energy to conclude the period of fire-cooking and begin the period of fireless-cooking, and means independent of the said cocking means and of the said automatic operating 35 means for the control and regulation of the said fuel-supply.

20 20. In a cooking apparatus for conjoint

fire- and fireless-cooking, the combination with a cooking compartment, of a burner arranged in heating relation thereto, a fuel-supply, means for storing energy for terminating the period of fire-cooking at a predetermined point therein, cocking means for releasing the energy so stored, automatic operating means for releasing the cocking means and so permitting the stored energy to conclude the period of fire-cooking and begin the period of fireless-cooking, the said automatic means being adapted to be manually set for the variable control of the 50 period of fire-cooking, whereby the relation of the period of fire-cooking to the period of fireless-cooking may be prearranged by the operator prior to the use of the apparatus, and means independent of said energy storing means, cocking means, and automatic operating means, for the control and regulation of said fuel-supply.

25 21. In a cooking apparatus for conjoint fire- and fireless-cooking, the combination with a cooking compartment, of a burner arranged in heating relation thereto, a fuel-supply, means for storing energy for terminating the fuel-supply, cocking means for restraining the energy so stored, automatic 60 operating means for releasing the cocking means and permitting the termination of the fuel-supply, and means independent of the energy storing means, cocking means and automatic operating means, for the manual 65 regulation and control of the said fuel-supply.

In testimony whereof, I have signed my name to this specification, in the presence of two subscribing witnesses.

ROSS M. G. PHILLIPS.
